UNITED STATES PATENT OFFICE.

ALMA MÜTZELL, OF BRESLAU, GERMANY.

HOLDER FOR SEWING IMPLEMENTS AND MATERIALS OR THE LIKE.

No. 893,643.

Specification of Letters Patent.

Patented July 21, 1908.

Application filed July 16, 1906. Serial No. 326,452.

To all whom it may concern:

Be it known that I, ALMA MÜTZELL, *geborene MULERT*, a subject of the German Emperor, residing at Breslau, in the Empire of Germany, have invented an Improved Holder for Sewing Implements and Materials or the Like, of which the following is a specification.

The invention relates to an improved holder for sewing implements and materials or the like such as spools of cotton thread, thimbles, scissors, pins, buttons, hooks, eyes, darning wool, metal crochet hooks, knitting needles, pins and the like, in short for sundry objects which hitherto have been placed in boxes, drawers and the like.

The holder consists essentially of a base plate on which are fixed besides a pincushion several vertical pins or rods as well as various tubes, funnels and receptacles of various widths and heights.

The annexed drawing illustrates the invention in which

Figure 1 is a plan view of the holder. Fig. 2 a section on line A—A of Fig. 1.

B indicates the base plate.

a is the pincushion; b the vertical pins or rods on which spools of cotton c or the like can be placed or balls of woolen or the like thread can be arranged and on which the thimble d or the like may be placed. The tubes, funnels or receptacles e f g serve according to their height and width for receiving different implements. For instance, the tube f is suitable for darning needles to be inserted therein, the receptacles g for buttons, hooks, eyes and the like and the tube e for

longer and higher implements such as knitting needles, crochet hooks and the like. The tube e is arranged telescopically so that it can be adjusted with regard to its height to suitably receive implements of different lengths as required. The pins b are similarly constructed, that is to say, are provided with sleeves h by means of which their height can be adjusted.

The improved holder has in comparison with closed receptacles the advantage that the implements or materials arranged thereon lie freely to hand and are in place and ready for immediate use.

What I claim as my invention and desire to secure by Letters Patent of the United States is:—

1. A device of the character described comprising a base plate, vertical pins mounted thereon, and a plurality of vertically adjustable and variously sized receptacles also mounted on said base plate substantially as set forth. 55

2. A device of the character described comprising a base plate, a pincushion thereon, vertical pins mounted on said base plate and adjustable as to height and a plurality of variously sized telescopically adjustable receptacles also mounted on said base plate substantially as set forth. 60 65

In witness whereof I have signed this specification in the presence of two witnesses.

ALMA MÜTZELL
